UNITED STATES PATENT OFFICE.

OLAV OVERGAARD, OF BROOKLYN, NEW YORK, ASSIGNOR TO STAR CONTRA PROPELLER LTD. A/S., OF OSLO, NORWAY, A CORPORATION OF NORWAY.

REMOVABLE CONTRAPROPELLER.

Application filed November 25, 1927. Serial No. 235,511.

This invention relates to contra-propellers of that class where the contra-propeller blades are attached or made integral with the rudder post. Where contra-propellers of this description are used, the rudder post is made separable from the stern post and skeg so that it may be removed when the main propeller has to be drawn off the propeller shaft. It sometimes is necessary or 10 desirable to remove the propeller from the propeller shaft without putting the boat in drydock. This can be done by shifting the load of the boat forward until the boat is tipped enough so that the hub of the propeller comes above the water level. It is 15 much more difficult, however, to bring the lower end of the rudder post to the surface. My invention provides for the removal of the rudder post out of line with the propeller without the necessity of detaching the 20 same from the vessel at the lower end. To this end, the invention comprises a contra-propeller hinged at the lower end and bolted at the upper end on a pivot with a fore and aft axis to the stern post. Such a contra-propeller when unbolted at the upper 25 end can be lowered away sidewise of the ship on its hinged lower end until it no longer interferes with the removal of the main propeller.

An embodiment of the invention is illustrated in the accompanying drawings, in which

Figure 1 is a side elevation of the stern part of a ship fitted with a contra-propeller of the above description.

Figure 2 is a rear end view of the same.

The stern post is shown at 1, the rudder at 2, the skeg at 3, the main propeller at 4 and the contra-propeller at 5 equipped with contra-propeller blades 6. These 40 blades, of which two are shown as forming the vertical part of the contra-propeller

and two extending laterally from the same, are so contoured as to catch and turn into 45 a direct rearward motion the rotating stream that is discharged from the main propeller.

At 7 is shown a hinge having a fore and aft axis connecting the lower end of the contra-propeller to the skeg and at 8 are 50 shown bolts whereby the upper end of the contra-propeller is secured to the stern post. When it is desired to remove the main propeller, the ship may have its stern raised enough to bring the hub of the main propeller above the surface of the water by 55 weighting the forward part of the vessel, then after removal of the bolts 8 the contra-propeller can be lowered by the aid of a block and fall or other means until it, by 60 swinging sidewise on its hinge 7 occupies a position such as shown by dotted lines in Figure 2, in which position it will be entirely out of the way of the rearward movement of the main propeller in the process of sliding 65 it off its shaft. When the propeller has been replaced the contra-propeller can be hauled up out of the water and rebolted at the top.

I claim:—

1. The combination with the main propeller of a vessel, of a contra-propeller in axial alignment therewith, the said contra-propeller having at its lower end a pivotal support adapted to allow the contra-propeller to be swung sidewise out of line with the main propeller for the purpose of removing the latter.

2. The combination with the main propeller of a vessel, of a contra-propeller in axial alignment therewith, the said contra-propeller being bolted to the vessel at its upper end and supported at its lower end by a pivot, the axis of which is fore and aft.

OLAV OVERGAARD.
